UNITED STATES PATENT OFFICE

2,194,136

BURNER FOR LIQUID FUEL

James L. Breese, Santa Fe, N. Mex., assignor, by
mesne assignments, to Motor Wheel Corpora-
tion, Lansing, Mich., a corporation of Michigan

Original application September 11, 1937, Serial
No. 163,369. Divided and this application
March 14, 1938, Serial No. 195,727

3 Claims. (Cl. 158—91)

My invention relates to an improvement in burners for liquid fuels, such as hydrocarbons, and has for one purpose the provision of a burner which can be turned down to a very small fire, 5 or low draft, without destroying the characteristic mode of combustion described, for example, in my prior issued Patent No. 1,702,929, issued February 19, 1929.

Another purpose is the provision of means for 10 permitting low draft burning with such a burner while preventing down drafts from upper portions of the combustion chamber which would disadvantageously affect combustion.

Another purpose is the provision of such means 15 which are adaptable for ready removal to permit easy cleaning of the burner and for adjustment of the burner capacity.

Another purpose is the provision, in connection 20 with one of my burners, of a lower supplemental burner which may have the function of a pilot light for maintaining combustion during periods when a minimum heat or no heat is desired.

Other purposes will appear from time to time 25 in the course of the specification and claims.

The present application is a division of my application Serial No. 163,369, filed September 11, 1937.

I illustrate my invention more or less diagrammatically in the accompanying drawing, wherein:

30 Figure 1 is a vertical section;

Figure 2 is a vertical section on an enlarged scale of a portion of the device showing a variant form of baffle with the baffle in side elevation;

Figure 3 is a section similar to Figure 2 showing a still further variation with the baffle in side elevation;

Figure 4 is a view through a variant form similar to Figures 2 and 3 on a smaller scale.

Like parts are indicated by like symbols 40 throughout the specification and drawing.

Referring to the drawing, 1 generally indicates an outer furnace or heater shell and 2 an inner shell. 3 is a horizontal partition secured to the inner shell and provided with a central aperture 4. 5 is a preferably removable baffle with a central aperture 6. 7 is a combustion chamber member, herein shown as generally cylindrical, with a bottom 8 which may be formed, if desired, in one piece and which may be secured in any 50 suitable way as by bolts or welding 9 to the member 3.

10 is any suitable fuel supply pipe extending to the bottom 8. The means for supplying the fuel is not herein shown since it does not of itself form part of the present invention, but it will be understood that any suitable float chamber or the like may be employed for governing the desired flow of fuel, for example a liquid hydrocarbon fuel, to the bottom 8.

60 11 is a closure member secured within the shell

2 and provided with apertures 12 which may be in a separate removable plate 13 closing the central aperture 14 of the member 11. I herein illustrate air inlet apertures 15 in the bottom of the shell 2 and it will be understood that any suitable means, whether by natural draft or by forced draft, may be used to supply air to the space between the shells 1 and 2, which air is caused to flow through the apertures 15, upwardly through the apertures 12, and into the space 10 between the member 7 and the shell 2. The member 7 is provided with an upper row of secondary air inlet apertures 16, herein shown as upwardly and inwardly inclined. A plurality of 15 preferably smaller apertures 17 are shown arranged in rows in a lower portion of the member 7. The bottom row of apertures 18 is also indicated.

Referring to Figure 1, I illustrate a removable baffle ring 19 in the form of a spiral having an arc 20 of about 360 degrees. It will be realized that this element may be formed with a greater or a lesser arc, but 360 degrees is a convenient length. The lower end is shown as at 20 resting upon the bottom of the chamber 7. It will be noted that 25 the spiral baffle 19 includes an upper portion 20a which extends above the level of the lowest row of holes 18. Any suitable additional means may, if desired, be employed in order to permit the position or support of the baffle 19. I illustrate, 30 for example, an inwardly extending lug 21 for supporting an intermediate portion of the baffle and additional lugs may, if desired, be employed. However, if the baffle is formed to conform substantially in its exterior periphery to the inner 35 face of the wall of the member 7, no additional means are necessary. Under some circumstances, however, I prefer to have a perceptible air space between the outer edge of the baffle and the inner face of the member 7, and in such 40 event the supporting members 21 may be desirable.

Referring to Figure 2, I illustrate a baffle 19a similar to the baffle 19, but located between the top and bottom of the chamber 7, and extending 45 entirely above the bottom apertures 18. A plurality of the supporting members 21 may be employed in order to position the baffle or any other suitable supporting means may be employed. It will be understood that whereas in the drawing 50 the baffle is shown as engaging the inner face of the wall 7, it may be spaced outwardly therefrom if desired, and under some circumstances I prefer to have the circulation of air upwardly about the outer edge of the baffle and along the 55 inner face of the wall 7.

Referring to Figure 3, I illustrate a spiral baffle 19b which extends substantially from top to bottom of the chamber but which is shown as terminating short of the secondary air apertures 60

16. In general, no supporting means are necessary as the lower end of the baffle simply rests on the bottom. If desired, I may position a plurality of members 21 to support the baffle.

5 Referring to Figure 4, I illustrate in addition to the bottom baffle 19 a similar spiral baffle 19c located above the baffle 19 and preferably extending adjacent the upper portion of the chamber 7. I illustrate it, however, as terminating short of the secondary air aperture 16. It may be mounted for example on a plurality of inwardly extending members 21.

10 It will be realized that whereas I have described and shown a practical and operative device, nevertheless many changes in size, shape, 15 number and disposition of parts may be made without departing from the spirit of my invention. I therefore wish my drawing to be taken as in a broad sense illustrative and diagrammatic 20 rather than as limiting me to the specific details as shown herein.

The use and operation of my invention are as follows:

25 In the normal operation of the device the characteristic combustion method of my Patent Number 1,702,929 may be carried on. The primary air supply enters through the apertures 17 and mixes with the hydrocarbon vaporized by the combustion. The heat of combustion, once 30 the device is in operation, vaporizes the hydrocarbon and the vaporized hydrocarbon rises and mixes with the primary air supply to form a primary mixture. This primary mixture moves upwardly toward and through the aperture 6 of the baffle 5 and there receives the secondary air supply which is admitted through the apertures 16. This produces a final mixture which burns and provides the heat for the stove or furnace unit.

35 Preferably, whether by natural draft or by 40 any suitable fan or the like, not herein shown, sufficient air is admitted for maintaining combustion at a rate sufficient to give the desired heat. Any suitable control means, thermostatic or otherwise, may be employed for controlling 45 the desired heat produced.

In the event that it is desired to turn down the unit to a minimum heat, or to practically no heat, the air supply is reduced and combustion is correspondingly reduced. In the structure 50 as shown in my Patent Number 1,702,929, there is a limit below which the stove does not operate efficiently. For example, unless a sufficient air supply and sufficient rate of combustion is maintained, the secondary air or the air above 55 the baffle 5 tends to eddy back and circulate down into the primary combustion zone, with the result that the balance between the primary and secondary zones is destroyed and my method of combustion is interrupted, resulting in carbon 60 deposit and inefficient combustion.

I find that the interposition of a baffle, such as the one shown herein at 18, prevents this down draft and my primary mixing and combustion may be carried on by means of the holes 18, and 65 the secondary air may then be supplied by some or all of the holes 17. In other words, the primary zone moves down to or is limited to the holes below the baffle, and the holes above the baffle which previously operated as a source of 70 primary air then become the source of secondary air.

In practice, and depending upon the size and shape of the burner, the fuel used and draft conditions, there is some difficulty in positioning the baffle at the right point for a maximum turndown and in controlling combustion conditions adequately to permit a maximum turndown, while permitting initiation of combustion with the baffle in place. I find that a spiral baffle, such as I have shown herein at 19 and 19b, the maximum turndown may be obtained by having a spiral baffle extend to or be located in the bottom of the chamber 7. However, the fact that a spiral is used and not a closed or solid baffle member or ring, is advantageous in that when combustion is initiated as by dropping a piece of burning waste into the bottom of the chamber, enough air flows in through the apertures above the apertures 18 to support combustion and to permit the device to be heated up and to begin its normal function. I thus find that with the 20 spiral type of baffle herein shown, I get a maximum turndown without interfering with the normal launching of combustion. After combustion is once launched, the fuel can be turned down to a minimum and the fire will burn with 25 a blue flame. With the pot in the bottom zone of the chamber 7, as the rate of flow of fuel is increased by the turning of any suitable valve means controlling the fuel inlet, the combustion rises higher and higher in the chamber until 30 finally full combustion is taking place. In the earlier stage of the combustion, when only a small supply of fuel is admitted, the bottom row of apertures, or that part of them which are below the baffle, supply the primary air and the 35 rows of apertures above the lowest part of the baffle supply the secondary air. As the flow of fuel is increased, the next higher apertures are converted into primary apertures and the zone of division between primary and secondary air 40 rises along the baffle. Under some circumstances it may be advantageous to carry the baffle all the way up to the top of the pot, though I find that the form of Figure 1 is highly practical. Figure 2 is a form which permits only of a somewhat higher turndown, but which is highly practical where a low turndown is not necessary.

I claim:

1. Combustion apparatus comprising a hydrocarbon burner of the vaporizing pot type, said burner including a mixing chamber having a plurality of air inlet apertures in the wall thereof located in a plurality of vertically spaced horizontal rows, means for admitting a liquid hydrocarbon to the mixing chamber, and a spiral baffle 55 having an arcuate length of at least 360 degrees located intermediate the top and bottom of said mixing chamber, said baffle having a central aperture therethrough providing communication between the upper and lower portions of the 60 mixing chamber and intersecting the plane of at least one row of air inlet openings.

2. Combustion apparatus as defined in claim 1, wherein the radially outer edge of said spiral baffle conforms generally to and closely approaches the inner face of the mixing chamber wall.

3. Combustion apparatus as defined in claim 1, wherein the baffle intersects the plane of at least two rows of air inlet openings.

JAMES L. BREESE.
